UNITED STATES PATENT OFFICE.

JOHN DE VRIES, OF PASSAIC, NEW JERSEY.

FEED-WATER HEATER.

SPECIFICATION forming part of Letters Patent No. 478,315, dated July 5, 1892.

Application filed March 10, 1892. Serial No. 424,401. (No model.)

To all whom it may concern:

Be it known that I, JOHN DE VRIES, a citizen of the United States, residing at Passaic, Passaic county, New Jersey, have invented 5 certain new and useful Improvements in Feed-Water Heaters, fully described and represented in the following specification and the accompanying drawings, forming a part of the same.

10 The object of this invention is to furnish an economical and effective construction for feed-water heaters and one in which the water shall be forced positively through the entire circuit of the heating-tubes. In this construction the water is also conducted through a settling-chamber before it is heated to the boiling-point.

15 The invention will be understood by reference to the annexed drawings, in which—
20 Figure 1 is a vertical elevation of the apparatus with the parts in section at the center line where hatched. Fig. 2 is a plan of the tube-plate with a circle *v* to indicate the space in which the tubes are inclosed, and
25 Fig. 3 an edge view of the same. Fig. 4 is a plan of the base with the tube plate and shell removed.

30 To illustrate the invention, a heater of certain capacity is shown, containing two sets of tubes, with seven tubes in the center set and five tubes in the outer set; but the heater may be constructed with three or more sets of tubes, and a greater number of tubes may be provided in each set where the proportions of 35 the shell admit of such arrangement.

35 *a* is the base, provided with supporting-legs *b* and flange *c*, to which the tube-plate *d* is attached by bolts *e*. A cylindrical shell *f* is secured to the tube-plate by the same bolts 40 passed through flanges *g* from the bottom of the shell. Steam circulates through the shell by an inlet-pipe *h* at the top, and an outlet-pipe *i* near the bottom. The tube-plate is formed with four rows of tube-holes *u* and *u'*, 45 and the base is formed with four corresponding slots *k* *k'* and *l* *l'*. Two sets of arched or U-shaped tubes *t* and *t'* are secured to their lower ends in the holes *u* and *u'*, respectively, the tubes *t'* being bent to arch over the tubes 50 *t*, as shown in Fig. 1. The ends of the tubes are expanded in the holes of the tube-plate,

as is customary with tubular constructions, and the use of screw-threads is thus avoided, while the bending of the tubes into arch form secures a continuity of each tube from 55 one end to the other, and thus avoids the risk of leakage by any form of coupling. The cylindrical shape of the shell accommodates seven of the tubes *t* with five of the tubes *t'* arched over the same. The base is cored out 60 to connect the slots *k'* and *l*, passages *o* being formed through the metal beneath the slot *k*. An outlet *n* is connected with the slot *l'*, and the tube-plate is secured upon the base with an intervening packing *p*, which connects the lower ends of the pipes positively with the several slots.

With the construction described, the feed-water entering by the inlet *m* passes upward through the slot *k* into one leg of all the tubes 70 *t* and downward through the other leg and slot *k'* into the slot *l*. The water thence enters one leg of all the tubes *t'* and passes downward through the other leg into the slot *l'* and thence outward by the pipe *n*. A settling-chamber *q* is formed in the base beneath the slot *k'*, and the passages *o* are extended from such chamber above its bottom into the slot *l*, thus permitting the movement 75 of the water through the chamber from the tubes *t* to the tubes *t'* without disturbing any sediment that may settle in the bottom of the chamber. A cock *r* is provided to blow off the sediment from the chamber *q*. The steam in the shell *f* heats the tubes *t* and *t'* equally, 80 and the movement of the feed-water through the tubes *t* obviously heats it in a partial manner only before it reaches the settling-chamber, and the sediment which is precipitated by such heating is thus deposited in 85 the chamber before the water reaches a boiling-point. The water moving from the settling-chamber to the tubes *t'* is subsequently heated in a higher degree before it is discharged by the pipe *n*.

90 It is obvious that three or more sets of tubes may be used instead of two by forming additional pairs of slots outside of the slots *l* *l'* and providing suitable passages to connect such slots in a proper manner. The essential 95 part of the invention is the formation of the base with supporting-feet and with the set-

ting-chamber and required slots cast directly therein, one of the central slots being connected with the water-inlet *m* and an adjoining central slot being connected with the settling-chamber so as to receive the sediment when the water is partially heated. With this arrangement the precipitate is deposited in the settling-chamber while the water passes in succession through all the sets of tubes.

10. What I claim as my invention is—

1. The combination, in a feed-water heater, of the shell *f*, provided with steam-pipes *h* and *i*, the tube-plate *d*, having the U-shaped tubes *t t'* secured therein as described, and the base *a*, provided with supporting-feet and cast with the settling-chamber *q* and the slots *k k'* and *l l'*, as set forth, the slot *k* being connected with the water-inlet *m*, the slot *k'* being connected with the settling-chamber *q* and by the passages *o* with the slot *l*, and the slot *l'* being connected with the water-outlet *n*, and the settling-chamber being provided with the blow-off cock *r*, the whole arranged and operated as herein set forth.

15. provided with supporting-feet and cast with the settling-chamber *q* and the slots therein, as set forth, one of the central slots *k* being connected with the water-inlet *m* and the adjoining slot *k'* being connected with the settling-chamber *q* and the slot *l* and one of the outer slots being connected with the water-outlet *n*, and the settling-chamber being provided with the blow-off cock *r*, the whole

arranged and operated substantially as set forth.

2. The combination, in a feed-water heater, of the shell *f*, provided with steam-pipes *h* and *i*, the tube-plate *d*, having the U-shaped tubes *t t'* secured therein as described, and the base *a*, provided with supporting-feet and cast with the settling-chamber *q* and the slots *k k'* and *l l'*, as set forth, the slot *k* being connected with the water-inlet *m*, the slot *k'* being connected with the settling-chamber *q* and by the passages *o* with the slot *l*, and the slot *l'* being connected with the water-outlet *n*, and the settling-chamber being provided with the blow-off cock *r*, the whole arranged and operated as herein set forth.

In testimony whereof I have hereunto set my hand in the presence of two subscribing witnesses.

JOHN DE VRIES.
